United States Patent

Des. 237,871
Patented Dec. 2, 1975

237,871

REPRODUCTION MACHINE STACKING CART

Jacob W. Patla, Fairport, N.Y., assignor to
Xerox Corporation, Stamford, Conn.

Filed Dec. 27, 1973, Ser. No. 428,936

Term of patent 14 years

Int. Cl. D12—02

U.S. Cl. D12—26

FIG. 1

FIG. 2

FIG. 3

FIG. 4

FIG. 1 is a front perspective view of a reproduction machine stacking cart showing my new and ornamental design;

FIG. 2 is a front elevational view thereof;

FIG. 3 is a side elevational view thereof, the opposite side being identical thereto; and

FIG. 4 is a side perspective view thereof.

I claim:

The ornamental design for reproduction machine stacking cart, as shown.
